UNITED STATES PATENT OFFICE

SAMUEL E. ALLEN, OF PITTSBURGH, PENNSYLVANIA

TAG-MAKING MACHINE

Application filed July 13, 1928. Serial No. 292,455.

This invention relates to shipping-tag making machines.

The primary object of this invention is to provide an automatic machine having correlated mechanisms for successively punching out the eyelet holes, applying thereto strengthening washers or patches, inserting a metallic eyelet into the priorly punched hole, cutting the corners of the tags and delivering the finished tags onto a discharge table or endless conveyor. Another object of this invention is to provide in such a machine means for stamping the eyelet reinforcing patches out of continuous strips and for automatically applying a coat of glue on one side thereof. A further object resides in a machine of this character adapted for making shipping-tags of greatly varying sizes. Still another object is the provision of a tag making machine which is relatively simple in construction very compact and reduced in size and in which the mechanisms performing the various necessary functions for producing a finished tag are operated in proper speed and time relation from a single source of power, preferably from an electric motor. Yet another object is to provide on such a machine means whereby some of the mechanisms performing specific functions may be quickly disconnected without in any way affecting the operation of the remaining mechanisms. Additional features and advantages of this invention will appear from the following description considered in connection with the accompanying drawings forming a part of this application, and in which:

Fig. 1 is an elevation of the right hand side of my machine, in relation to the feeding end, with the eyeleting machine only suggestively indicated in dot and dash lines.

Fig. 2 is an elevation of the left hand side of the machine, the eyeleting machine being also outlined in dot and dash lines.

Fig. 3 is a top plan view of the complete machine.

Fig. 4 is a top plan view of the patch-strip feeding mechanism.

Fig. 5 is a fractional elevation of one side, 50 and

Fig. 6 is an elevation of the other side of said mechanism.

Fig. 7 shows the right hand end elevation of the same.

Fig. 8 is a front elevation of the eyelet patch punching and pressing mechanism, and the driving means therefor.

Fig. 9 is a side elevation of Fig. 8, showing also parts of the eccentric drives for the patch-strip feeder and the eyeleting mecha- 60 nism.

Fig. 10 represents a side view of the patch-strip gluing device.

Fig. 11 is a front view of Fig. 10.

Fig. 12 shows a section taken through the feeding head of the gluing device.

Fig. 13 is a top view of the upper feed opening of the same.

Fig. 14 is a sectional view taken on line 14—14 in Fig. 12.

Figs. 15 and 16 are respectively fractional sectional views taken on line 15—15 and 16—16 in Fig. 10.

Fig. 17 is a top plan view of the tag stopping mechanism.

Fig. 18 is a side elevation of Fig. 17.

Fig. 19 represents a front elevation of an operating lever used with same mechanism.

Fig. 20 is a front elevation of Fig. 17, the operating lever having been omitted.

Fig. 21 illustrates the main drive shaft of the machine with the various elements mounted thereon shown in section.

Fig. 22 is an end view of Fig. 21.

Fig. 23 is a perspective diagrammatic view showing the controlling means for the patch-strip feeding mechanism.

Fig. 24 is a detail view showing the operating lever and the cam-rail for the tag-stopping mechanism.

Fig. 25 is a top plan view showing the eyelet magazine and eyelet raceway.

Fig. 26 represents a sectional view taken on line 26—26 in Fig. 25.

Fig. 27 is a side view of one of the push-rods used for feeding the stacked up tag-blanks, one at a time, into the machine.

Fig. 28 shows the method of adjustably mounting two push-rods on a supporting rod.

Fig. 29 is a side elevation of the tag jog- 100

ging mechanism used for pushing the tags transversely of the machine in proper punching and eyeleting positions.

Fig. 30 is a top view of Fig. 29.

Fig. 31 shows an enlarged side view of parts of the jogging mechanism.

Fig. 32 is a top view of Fig. 31.

Fig. 33 represents a cross section taken on line 33—33, in Fig. 32.

Fig. 34 is a side view of the jog-finger, and Fig. 35 is a rear elevation thereof.

Fig. 36 is a plan view of the control mechanism for the eyeleting machine and adjacent parts.

Fig. 37 is a side elevation of Fig. 36.

Figs. 38 to 42 are perspective views of some of the structural elements shown in Figs. 36 and 37.

Fig. 43 is a perspective view showing especially a side elevation of the eyeleting mechanism.

Fig. 44 is a front elevation of said mechanism, with some parts removed, and

Fig. 45 is a top view thereof.

Figs. 46 to 49 are fragmentary sectional views showing different operative conditions of the eyeleting machine.

Fig. 50 is a fragmentary view showing the feeding end of the eyelet-machine, some parts being removed.

Fig. 51 is a fractional perspective view showing a slide-plate used for controlling the operation of the eylet-pilot of the eyeleting mechanism.

Figs. 52 and 53 show the eyelet-pilot in non-operative and operative positions.

Fig. 54 is a fractional sectional view through the guide-bushing of the eyelet-pilot.

Figs. 55—56 show respectively a top view and a side view of the feeding end of the eyelet raceway.

Figs. 57 and 58 show two operative positions of the operating mechanism of the eyeleting machine.

Figs. 59 and 60 are sectional views illustrating the positions occupied by the slide head when in the operative positions shown in Figs. 57 and 58.

Fig. 61 is a detail fragmentary view showing the operating cam and roller for the eyeleting machine.

Fig. 62 shows one method of supporting two reels of patch-strips.

Fig. 63 represents a cross-sectional view taken on line 63—63, Figs. 48, 49, through the column portion of the eyeleting device.

Fig. 64 is a sectional view taken on line 64—64, Figs. 48 and 49, through the base portion of the eyeleting device, showing also various adjacent parts.

The pre-cut blanks used for making the tags are piled up on the stationary feed table 1 and supported by the horizontal bars 2 and 3 slidably secured on a transverse

rod 4 supported in a manner to be described later on the feed table. The stack of tag-blanks is properly guided and aligned vertically by means of the lateral guide-plate 5, by the two adjustable front gauges 6 and by the lateral gauge 7. The guide-plate 5 is adjustably held by a screw 8 to the support 9 secured on the right side of the feed table. The various gauges are also longitudinally and transversely adjustable, they being held by thumb-screws 10 placed on top of the special blocks 11 which slidably receive the horizontal arms 12 of the gauges and which are adjustably slidable on the transverse bridge 13, the ends of which are secured to the sides of the feed table.

The power required for operating the machine is preferably obtained from an electric motor 14 the pinion 15 of which meshes with the main gear 16 mounted on the main shaft, the construction of which, as best shown in Fig. 21, comprises the solid through-shaft 17 on the reduced portion 18 of which is freely mounted the hollow shaft 19 upon which the main gear 16 is keyed.

Screwed to the gear 16 is a circular plate 20 to which is fastened the chain-sprocket 21.

At the inner end of the hollow shaft is keyed the eccentric 22 and at the outer end is similarly fastened the fly-wheel 23. Adjacent

this wheel is mounted on the through-shaft 17 the index dial 24 upon which are cut graduations 25 by means of which the two shafts and elements mounted thereon may be ad-

justed in proper angular relation, and locked therein by means of the bolt 26 screwed in

the fly-wheel and engaging a circular slot 27 provided in the index dial. These shafts

run in bearings 28 and 29 provided on both sides of the housing 30 of the machine. Out-

side of the bearing 29 are mounted on the through-shaft the two eccentrics 31 and 32 for the patch-punch, the cam 33 for the eye-

leting device and the crank-disk 34 for the patch-strip feeding device.

Slidably mounted in grooves 35 provided in the feed table is the feed-carriage 36 having a cross-piece 37 longitudinally adjustable thereon by means of the screw and slot con-

nection 38. On the feed-carriage are mount- ed for longitudinal and transverse adjust-

ment the push-rods 39 in a manner illustrat-

ed especially in Figs. 27 and 28.

Each push-rod consists of a horizontal rod 40 to which is secured at one end for limited

rocking movement by means of the pin and slot connection 41, a tag-pusher 42 comprising the downwardly inclined push-finger 43, the central portion 44 and the hub por-

tion 45 which receives the end of the rod 40. On top of the central portion is fas-

tened by a screw 46 a hardened steel plate 47 which extends a slight distance above the upper end of the finger 43 so as to engage

130

5 The push-rods are each longitudinally secured by means of the screws 49 in a block 50 which in turn is slideable on one arm of the transverse yoke 51, and held in proper position by set-screws 52. The yoke is rockably carried at the center by the support 53 on the feed-carriage.

10 The latter is operated from the main shaft by means of the longitudinally adjustable connecting-rod 54 having one end fastened by means of the pin connection 55 to the piece 37 of the feed-carriage 36, and the other end hingedly and adjustably connected to the slotted end of the lever 56 angularly 15 adjustable on the intermediate shaft 57. On this same shaft is also adjustably mounted the substantially horizontal lever 58. Both levers are secured on this shaft by means of clamping-bolts 59, and the shaft is supported 20 in bearings 60 provided in both sides of the housing 30. The intermediate shaft is oscillated by means of a connecting-rod 61 connected at the upper end to the lever 58 and at the lower end to the eccentric 22 positioned on the main shaft.

25 The tag-blanks pushed forward by the push-fingers are engaged by the feed-rolls 62 and 63, and are then delivered between the two sets of endless conveyor belts 64 and 30 65.

35 The two feed-rolls are rotated in opposite directions by means of the sprocket 21, Fig. 21, and the sprocket chain 66 which is trained about the upper sprocket 67 running on a stub-shaft 68 mounted in a special housing 69. Fastened to the sprocket 67 is a gear 70 meshing with a gear 71, keyed on the shaft 72 of the lower belt conveyor 64. Gear 71 meshes with the small idler gear 40 73 which, in turn, operates the gears 74 and 75, mounted respectively on the lower and upper feed-rollers 62 and 63, in opposite direction.

45 To prevent more than one card being delivered to the conveyors at the same time, I provide the limit-gauge 76 the height of which above the lug 3 may be accurately adjusted by means of the micrometric screw adjustment 77, and locked in the correct position by the lock nut 78 against the bracket 79 slidably secured on the transverse rod 80 supported at both ends by the standards 81 mounted on the top of the main housing 30. In these standards are also placed the bearings for the feed-rolls 62, 63. The transverse rod 4 carrying the lug 3 is likewise supported by these standards.

50 The lower conveyor belts 64 run over pulleys 82 mounted on the front shaft 72 and over the pulleys 83 and the drum 84 mounted on the rear shaft 85. The upper conveyor belts are trained about the front pulleys 86 and the rear pulleys 87; the former running at the ends of arms 88 rockably mounted 55 about the upper feed-roll 63, so that they will

bear on the lower pulleys, and the latter running freely on a stub shaft 89 positioned at the upper end of the support 90, in which one end of the rear shaft 85 is rotatably mounted. The other end of said shaft is supported for rotation by a bearing support 91 mounted on top of the main housing. The front shaft 72 runs in bearings provided in two similar supports 92. In order to insure sufficient adhesion between the upper and lower conveyor belts, to safely convey the tag-blanks, pressure rollers 93 mounted on hinged arms 94 are used.

60 It will be noted in Fig. 3 that only two upper conveyor belts and several more lower conveyor belts are used. This is done to reduce the number of parts on the machine, experience having shown that the upper belts need only be used near the ends of the tag-blanks in which the reinforcing patches and eyelets are to be applied.

65 The first operation performed on a tag-blank is that of punching out the reinforcing eyelet-patches, applying them to the tag-blank and punching the eyelet hole. This is done by means of a punch-press, a patch-strip feeding device and a patch-strip gluing device.

70 The punch-press, as shown in Figs. 8 and 9, comprises a vertical stand 95 securely bolted on a pedestal 96 provided on top of the housing 30. On this stand are mounted for vertical sliding movement the upper traveling head 97 and the lower traveling head 98, both properly guided by suitable guide-grooves cut in the stand 95 and by the guide-strips 99 and 100.

75 In the upper traveling head is mounted for vertical sliding movement the upper hollow patch-punch 101 engaging an open slot 137 and which is limited in its downward movement within the head by a collar 102. Said head has a substantially rectangular cavity open at the front, as shown at 103, and in this cavity are introduced the sliding gland 104 and the coil spring 105 inserted between the gland and the collar 102. The gland 104 has an outwardly threaded hollow extension 106 which engages a rotatable, double collared, ferrule 107 freely mounted in an open slot provided in the upper wall 108 of the cavity 103. The initial compression of the spring 105 may be regulated by turning said ferrule, and locked in position by means of the lock nut 109. Passing through the ferrule, the gland, spring and the upper patch-punch is the eyelet-punch 110 which is held in proper position, relative to the patch-punch, by means of a set screw 111 placed on the gland.

80 The lower patch-punch 112 is also hollow and has at its lower end a collar 113 adapted to fit inside an undercut and outwardly open slot 114 provided at the upper end of the lower traveling head.

85 Secured substantially at the middle of the

stand 95 is the punch-block 115 the two arms 116 and 117 of which are disposed in spaced parallel relation and are provided with the removable caps 118, 119 held by clamping bolts 120. In the arm 116 and cap 118 is secured the hardened steel guide-bushing 121 for the upper patch-punch, and in the arm 117 and cap 119 is secured a similar guide-bushing 122. Each bushing has at one end a collar 123 and at the other end a rectangular flange 124 in which is provided a through slot 125 adapted to receive and guide the strip of material from which the reinforcing patches are to be punched out. A through aperture 126 is provided in the stand for the passage of the used portion of said strip. The open space 127 between the flanges 124 receives the end of a tag-blank on which the patch is to be applied. The depth of location of the patch on the tag is limited by the wall of the punch-block, back of the flange 124. If patches are to be placed nearer the edge of the tag, spacers or shims may be inserted at the rear of the slot 127, as will be understood.

The upper and lower traveling heads, together with their respective patch-punches, are vertically and oppositely reciprocated by means of the connecting rods 128 and 129 respectively, the upper ends of which are hingedly connected, as at 130, 131, to said heads, while the other ends are screwed into the collars 132 and 133 of the eccentrics 31, 32 keyed in opposite relation on the main shaft 17. These connecting rods are longitudinally adjustable by means of turnbuckles 134, of usual design, engaging the oppositely threaded portions of said rods.

As the upper and lower patch-punches move toward each other, they will first punch a patch out of their corresponding patch-strips, to which glue has been applied on one side in a manner described hereafter, and press said patches on the tag-blank whereon they will stick. Upon further motion, the lower punch will force up the upper one against the compression spring 105 whereby the eyelet punch will come into action and punch the eyelet hole through the center of the patches and through the tag-blank. The punched out disc resulting therefrom is forced through the central hole in the lower punch and discharged into an open space 204 provided in front of the lower traveling head.

The method above described for fastening the upper and the lower patch-punches in their respective traveling heads is intended to facilitate the removal of said punches in the quickest manner, when in need of regrinding or cleaning. To this end, I provide on the lateral sides of the gland 104 pins 135 engaging L-shaped slots 136 cut in the sides of the cavity 103. These pins and slots serve to guide the gland in its rather limited vertical travel.

To remove the upper punch, the set-screw

111 is first loosened to allow for the extraction of the eyelet punch 110 and the gland 104 is raised by means of the lock-nut 109 until the patch-punch is released of the pressure from the spring 105. This enables the extraction of the latter through the open side of the cavity. The cap 118 is also removed by unscrewing the bolts 120 whereby the punch-guide sleeve 121, together with the punch 101 may be pulled out of place. The lower patch-punch and the guide-sleeve therefor are removed by simply unscrewing the cap 119, as will be readily understood.

The patch-strip feeding device is mounted on the top of the housing 30, back of the punch-press. As illustrated in Figs. 4 to 7 and 23, especially, this feeding device consists of a frame having a base 138 and an upright standard 139 to which is hingedly connected by the pin connection 140 the horizontal arm 141, having at the front a bearing-sleeve 142 which receives a shaft 143 upon which is mounted a gear 144 and the upper knurled feed-roll 145. The lower feed roll 146 and gear 147, meshing with gear 144, are keyed upon a shaft 148 running in a bearing support 149 cast on the base 138. On the other end of this shaft are also fastened a ratchet-wheel 150 and the outwardly disposed hand-wheel 151. The pressure of the upper feed-roll on the lower one may be regulated by means of a wing-nut 152 engaging threads on a vertical rod 153 secured to the base, said nut acting on a coil spring 154 resting on the arm 141.

Rockably mounted on the shaft 148 is a substantially U-shaped operating lever 155 having parallel arms 156, 157 provided with bearings for said shaft. On a flattened extension 158 on arm 157 is rockably mounted a pawl 159 having a ratchet-wheel engaging finger 160 and a tail piece 161. The operating lever is operated by means of a connecting rod 162 the lower end of which is suitably connected to the crank disc 34 fastened to the main shaft 17, whereas the upper end is hinged to the cross-arm 163 of said lever by the pin connection 164. As will be seen, the upward movement of the operating lever will cause the pawl 159 to turn the ratchet-wheel and, hence, feed the patch-strip 165 forward.

To prevent excessive rotation of the lower feed-roll, due to the momentum imparted thereto by the pawl, I provide an adjustable braking device which consists of a brake-shoe 166 bearing against the smooth central portion of the feed-roll 146 and the pressure of which may be adjusted and maintained by means of a pressure screw 167, placed in an extension 138a of the base 138, and the lock-nut 168.

The patch-strip material is supplied to the machine in the form of reels 169 which are rotatably mounted on pins 170 provided on

the two vertical arms of a suitable reel support 171, (Figs. 3 and 62) mounted on the left side of the housing. Side-shields 172 are used to insure the proper unwinding of the patch-strip, the outer shield being preferably supported by a metal rod 173 passing through the pins 170 and clamped thereto by thumb screws 174.

Before entering the punch-press, the patch-strips are each coated with glue, on one side only, by means of the gluing device fully shown in Figs. 10 to 16. This device consists of a tubular container 175 hingedly mounted on a rear pedestal 176 and freely supported at the front by the pedestal 177, both pedestals being supported by the top of the main housing. Liquid glue is poured in the container through the filling aperture 178 closed by a vented plug-cap 179. The glue is delivered to the patch-strip through the feed head 180 comprising a threaded cap 181 screwed onto the open end of the cylinder and having a substantially H-shaped extension comprising the inner leg 182, the cross-piece 183 and the outer leg 184. In the latter is provided a narrow through channel 185 of ample width to suit the width of the patch-strip used. This glue channel communicates with the interior of the container by the ducts 186 drilled through the portions 182 and 183. A removable plug 187 is screwed in the outer end of this duct for cleaning purposes.

Both ends of the glue channel are normally closed by shoes 188 mounted on the levers 189 hingedly connected to the feed-head at 190 and forced against the ends of the leg 184 by a coil spring 191. These levers have extensions 192 whereby they may be easily raised for inserting the patch-strips. The latter are guided through slots 193 provided in the guide-plate 194 screwed on one side of the feed-head. Moreover, the patch-strips are guided on their way from the reels to the glue-head by means of knurled guide-rollers 195, Figs. 3 and 62, suitably located on top of the housing.

Machines of this kind are often kept running idly and, in order to prevent any waste of patching material during such periods, I provide a patch-feed controlling device illustrated in particular in Fig. 23. It comprises a suitably bent latch-finger 196 fastened at the end of a shaft 197 running in bearings 198 in such a manner as to be depressed by each successive tag-blank 199 fed in the machine and carried forward between the lower and upper conveyor belts. At the outer end of shaft 197 is secured an arm 200 to which is hinged one end of the connecting rod 201, the other end of which is hingedly attached to a substantially vertical lever 202 rockably mounted in a slotted extension 203 provided on the arm 141 of the patch-feeder. This lever is positioned above and is adapted to engage the tail-piece 161 of the pawl 159, to

prevent the latter engaging the ratchet-wheel unless the latch-finger 196 has previously been depressed by a tag-blank into the releasing position indicated in dot and dash lines in Fig. 23. The latch-finger 196 is normally held in substantially vertical position by a spring 200 fastened at one end to the arm 200 and at the other end to the top of the main housing 30. When no tag-blanks are fed into the machine, the lever 202 will, of course, prevent the finger 160 engaging the ratchet-wheel and turn the same forward at every upward movement of the operating lever 155.

The next step in the making of shipping tags is the insertion and setting of the metal eyelets in the eyelet holes. The metal eyelets are stored in an angularly disposed barrel or magazine 205 mounted on the eyelet carriage comprising a magazine supporting arm 206 and a sole-plate 207 guided for transverse reciprocating movement by guides 208 screwed onto a base 209 securely bolted to the top of the housing and having at the front a vertical column 210. A spring 213 having its ends fastened to the arm 206 and to said column tends to normally pull the eyelet carriage toward the latter.

Guided for vertical sliding movement along the front of the column 210 by flanges 211, 212, is the lower eyelet sliding-head comprising two spaced vertical slide-bars 214 and 215 connected at the top by the cross-piece 216 having arms 217 extending at both sides of the column. At the lower ends of the slide-bars are secured by the pins 218 the eyelet pilot-head 219 having a sleeve portion 220, a securely held pilot-bushing 221 in which is frictionally held the eyelet pilot 222 by means of a pin 223 positioned at one end of a feather-spring 224 held by a screw 225. The eyelet pilot-head has a downward extension 226 to which is hingedly connected by the pin connection 227, (Figs. 57 to 61) the cross head 228 running between guides 229 secured at one side of the housing 30. The cross-head is vertically reciprocated by a connecting-rod 230 the lower end of which has a guide-slot 231 engaged by a portion of the main shaft 17. In this slot is adjustably secured by a studded bolt 232 the roller 233 adapted to ride over the periphery of the cam 33, also on the main shaft. A coil-spring 234 fastened to the pin 235 on the cross-head and the pin 236 on the inside of the housing 120 is used to insure a permanent yielding engagement between the roller and cam.

At the upper end of the lower slide-head is secured, between the bars 214, 215, the rack 237 which meshes with a rack-gear 238 rotatable on a pin 239 and placed between the two spacer-blocks 210^a. This rack-gear operates another rack 240 at the lower end of which is fastened the suitably shaped eyelet-setter 241, placed in direct alignment with 130

the eyelet-pilot. The rack 240 is guided for proper operation by bent side-plates 242 (Figs. 44 and 63), rigidly mounted on the column 210, and by a removable front-plate 243 inserted between the side-plates and supported therein by pins 244 riveted on a removable plate 245. Said pins are prevented from working out by a through-pin 246 passing therethrough. The side-plates 242 form 10 also the supports for the pinion-pin 239 and the spacer-blocks 210.

The purpose of making the plate 243 removable is to enable the quick extraction of the eyelet-setter 241, when in need of regrinding or other repair. For similar reasons, the 15 eyelet-pilot can be quickly extracted by a downward pull sufficient to overcome the friction due to the pressure-pin 223.

The eyelet-setter passes through a stripper 20 247 secured and guided for vertical adjustment by the screw 248 and the pin 249 engaging a slot 250. The purpose of the stripper is to strip off any tag which might cling to the eyelet-setter, in its upward movement. 25 At the free end of the stripper is slidably fastened, by screws 251, the tag-stop 252 which limits the feeding of the tag-blanks toward the eyeletting machine.

The eyelets stored in the magazine 205 are 30 led toward the eyelet-pilot and setter by means of a raceway 253 which communicates with the magazine through crenelated apertures 254 (Fig. 26), cut adjacent the bottom 255 of the magazine in the side wall 256 thereof. This raceway is built up of strips of metal properly disposed to provide a suitable channel to receive the eyelets 257 in "flange-down" position.

At the foot of the raceway there is provided 40 a stop-pawl 258 (Figs. 55, 56) acted upon by a spring 259 and limited in its movement toward the eyelet-channel by a stop-pin 260. The purpose of this pawl is to prevent the eyelets in the raceway running out 45 by gravity. The lower end of the raceway is supported for angular adjustment and for rigidity by a prop 261 hinged thereto and adjustably secured in a lug 262, on the arm 206, by means of a set-screw 263.

50 The stored up eyelets are fed into the raceway by a horizontal circular brush 264 (Fig. 25) mounted on the bottom of the magazine and removably fastened in any desired manner to a shaft 265 passing through the bottom 255 and guided for rotation in a bushing 266 at the top of the arm 206. Fastened at the lower end of this shaft is a lever 267 (Fig. 43) which is reciprocally rotated by means of a connecting-rod 268 hingedly connected thereto by a ball-joint 269. The other end of this rod is similarly connected to the outer arm of a horizontal lever 270 rockably secured by a screw 271 on a post 272 provided on top of one of the stationary guides 208. 65 At the inner end of the lever 270 is hingedly

connected one end of the link 273, the other end thereof being hinged to a lug 274 mounted on the arm 206. To the outer arm of this lever is also attached one end of the coil-spring 275, the other end of which is fastened to the guide 208 in the manner shown. The tendency of this spring is to rotate the lever counterclockwise, and it assists the spring 213 in moving the eyelet carriage toward the column 210.

Back of said column is a vertical slide-bar 276 having at the top a notch 277. This bar is guided freely for vertical movement by a sleeve 278 and is normally held down by a spring 308 having its ends attached to said bar and to the guide-bar 208. Adjacent the foot of the bar there is provided a spacer-pin 279 which limits the forward movement of the eyelet-carriage, respectively of the raceway 253 toward the eyelet-pilot.

On the eyelet-setter head is hingedly mounted in a pendent position, on a support 280, a latch 281 having at its lower end a hook 282 adapted to engage the notch 277. This latch is normally held in a flaring position shown in Figs. 46, 47 by means of a coil spring 283, and the amount of flaring is limited by the stop pin 284.

The latch 281 may be connected to the slide-bar 276 by means of a push-finger 285 placed at the inner end of the horizontal bell-crank lever 286, fulcrumed at 287 at one side of the column 210. The outer arm of this lever is hingedly connected by means of a suitably bent rod or wire 288, (Figs. 36 to 42) to the eyelet control trigger 289 rockably mounted on a lever 290 hinged on top of a longitudinally disposed bar 291 which also serves as a support for several conveyor belt pressure rollers 292. This trigger has at the top a pin 293 which freely engages the looped end of the control wire 288 and the lower end of the trigger is forwardly bent and extends below and between the conveyor belts in such a manner as to be engaged by the forwardly moving tag-blanks and rotated thereby in a clockwise direction. When the trigger is engaged by a tag-blank 199, Fig. 37, the push-finger 285 will bear on the latch 281 and push same into engagement with the slide-bar 276, as indicated in dot and dash lines in Figs. 46 and 47.

Rigidly secured to the eyelet-setter head by means of a plate 294 and screws 295 is the plunger-rod 296, at the lower end of which is laterally mounted, for rotation on a pin 297, the roller 298. This roller is adapted to engage the cam-shaped head 299 of the push-bar 300 (Figs. 48, 49), which is hingedly secured by a screw 301 to the arm 206 of the eyelet-carriage. The push-bar is guided at its free end by the bolt 302 engaging a slot 303 cut therein, and the bolt is supported by a bracket 304 securely mounted on the stationary base 209.

The head 299 comprises a downwardly inclined portion 305 and a protruding and straight nose portion 306 connected together by the curved portion 307. The purpose of 5 the plunger-rod 296 is to move the eyelet-carriage away from the eyelet-pilot, in a manner to be explained hereafter.

The operation of shearing the corners at the eyelet end of the tag-blank is also performed 10 on the eyeleting machine by means of the following mechanism: Two substantially similar shear supporting plates 309 are secured for lateral adjustment, in a vertical position, on horizontal parallel flanges 409 and 410 formed at the sides of the column 210, (Figs. 43, 44) by means of clamping bolts 310 and the clamping plates 311. These supporting-plates are each held in vertical position by guide-strips 312 formed integrally 15 thereon and adapted to slidably engage the slots 313 formed between the flanges 409 and 410. Each supporting-plate has at the top an extension 314 provided with an open slot 315 engaged by a trunnion-pin 316 on the collar 25 317 adjustably securable on the cross-arm 217 by a set-screw 318. Fulcrumed on a bolt 319 screwed on each supporting-plate is the upper shear-lever 320, the rear arm of which is hingedly connected to the trunnion-pin 30 316 by means of the longitudinally adjustable shear-connecting-rod 321. At the end of the front arm of each lever is adjustably secured by screws 322 the upper shear-blade 323. The latter cooperates with a lower 35 shear-blade 324, also adjustably secured by screws 325 on a bracket 326 screwed on, or otherwise fastened, to the shear-plate 309. On the shear supporting-plate nearest to the patch punch-press is a tag guide-plate 327, and on the other supporting-plate is mounted another, suitably shaped, guide-plate 328 to guide the sheared off corner pieces away 40 from the eyelet-pilot. A lip 329 is also formed on the left hand bracket 326 to guide 45 the tag-blanks under the shears.

The eyeleting and corner shearing device operates as follows:

Shortly before a tag-blank is carried in front of the eyeleting device, the control-trigger 289 causes the latch 281 to engage the slide-bar 276 when the tag-blank is in proper 50 position in front of the eyeleting device, for the pilot 222 to engage the eyelet-hole, the connecting-rod 230 raises the eyelet sliding head, thus also lifting the slide-bar 276. As 55 soon as the spacer pin 279 rises above the sole-plate 207, the spring 213 forces the eyelet-carriage forward in the position shown in Fig. 47, and the end of the raceway comes forward 60 into position to allow the upwardly moving eyelet-pilot 222 to engage the lowermost metal eyelet in the raceway. Upon further upward motion of the eyelet-head, the roller 298 on the plunger rod 296, Fig. 48, engages the cam-head 299 of the push-bar 300. This forces

the eyelet-carriage backwards and, therefore, the lowermost eyelet in the raceway is pulled out of the latter, against the retaining action of the stop-pawl 258, Fig. 55, and is left alone on the eyelet-pilot.

The upward movement of the connecting-rod 230 causes the eyelet-setter 241 and the eyelet-bushing 221, with its pilot 222, to close upon each other, thus inserting the metal eyelet in the patched and punched tag-blank, and gradually squeezing the eyelet onto the latter. When the roller 233, Figs. 57 to 61, has reached its highest point on the suitably shaped nose of the cam 33, the eyelet is fully squeezed on the tag-blank and the roller is then rapidly forced down on the circular portion of the cam by the spring 234. This, of course, causes the eyelet sliding head to move downward too, whereby the eyelet setter 241 and the pilot-bushing 221 separate. Should the eyeleted tag adhere to the eyelet-setter, it will be struck off by the stripper 247.

On the rapid downward movement of the eyelet-head, the slide-bar 276 reaches its lowermost position before the eyelet-head does, the roller 298 being still on the straight portion 306 of the cam-head 299. This breaks the engagement between the latch 281 and the slide-bar 276, and the former is forced into flaring position by the spring 283, as shown in Figs. 46 and 47, for instance.

The same operation is repeated for each successive tag-blank passing under the control-trigger 289. The forward and backward movement of the eyelet-carriage causes the connecting rod 268 to reciprocate the circular brush 264, thus continually driving the eyelets into the raceway.

During the squeezing operation of the eyelet, the frictionally held pilot 222 is pushed down into its bushing 221. It is again forced into protruding position above the bushing, on the downward motion of the eyelet sliding head by striking against a strike-lug 402 fastened on a slide-plate 403 slidably mounted below the base 209 of the eyeleting machine, as shown in Figs. 51 to 53. The slide-plate has at the rear a pull-handle 404 and at the front the two spaced legs 405 between which the extension 226 of the eyelet sliding head operates. These legs are downwardly bent at the front and connected together by a cross-piece 406 upon which the strike-lug 402 is secured. The latter has an open slot 407 adapted to be engaged by the pilot 222, the lower end of which carries a disc 408 larger than the width of the slot.

When tags are desired without the metal eyelets, the control-trigger 289 is disconnected from the eyeleting machine by removing the wire 288, whereby the feeding of the eyelets is prevented, as explained before. In addition, the slide-bar 403 is shifted and the pilot 222 pushed down so that the disc 408 will engage the underside of the strike-lug, see Fig. 52,

thus preventing the frictionally held pilot from moving up and down with the slide head. The locking of the eyelet-pilot is, therefore, an additional method of preventing the insertion of eyelets in the tags and is especially valuable in case the operator should forget to disconnect the control-trigger 289.

After leaving the eyeleting and shearing device, the finished tags are carried forward and deposited on the delivery table 330 of the machine. If desired, the delivery table may be substituted by an endless conveyor and a suitable tag-counting device, of any desired commercial type (not shown) may be connected to the machine.

The proper longitudinal positioning of the tag-blanks in front of the patch-punching and the eyeleting devices is obtained by a stopping device shown especially in Figs. 17 to 20 and 24. Transversely disposed on top of the housing 30 are the supports 331 and 332 having standards 333, 334 in which are rotatably mounted the two parallel and longitudinally disposed threaded spindles 335, which are held against longitudinal displacement by means of collars 336 bearing against the standards 333. On the threaded portions of each spindle are mounted suitably shaped nuts 337 upon which are fastened L-shaped, stationary, guide-bars 338 a certain distance away from the nuts to enable the insertion therebetween of the vertically movable stop-blades 339, in the top of which are cut open slots 340 to clear the various conveyor-belts.

The stop-blades are moved up and down by means of a longitudinally disposed square shaft 341 supported for sliding in special bushings 342 rotatably mounted on the guide-bars and in a bearing support 343.

Each stop-blade is operated by a curved lever 344 slidably mounted on the square shaft 341 and having a slot 345 engaged by a pin 346 fastened on the stop-blade and guided in a slot 347 cut in the vertical leg of the L-shaped guide-bar. Each stop bar is additionally guided against tilting by headed pins 348 fastened thereon and sliding in slots 349 also provided in the guide-plate.

Secured on the square shaft is a block 350 to which is rockably secured at 351 the normally horizontal operating lever 352, the head of which has two branches 353 in which are placed the adjusting screws 354 bearing against a lug 355 formed on the block. At the free end of the operating lever is a roller 356 adapted to engage the vertical leg of the L-shaped cam-rail 357, Fig. 24, fastened on the underside of the feed-carriage 36.

Adjacent the end of the shaft 341 is secured in a downward position a lever 358 to which is fastened one end of the tension spring 359, the tendency of which is to rotate the square shaft clockwise, to bring the stop-blades 339 into the lowered position shown in

Figs. 18 and 20. It will be noted that when the feed carriage moves toward the feed end of the machine, the roller 356 will climb the sloping end of the cam-rail 357, thus rotating the square shaft counterclockwise, against the pull exerted by the spring 359, and causing the stop-blades to rise sufficiently above the guide-bars to stop the two successive tag-blanks in their forward travel, directly in front of the eyeleting and patching devices, while the conveyor belts keep on traveling forward.

The space between the front and rear stop-blades 339 is made exactly equal to that between the centers of the patching and eyeleting devices. To allow for varying widths of tags being made on the machine, the two stop-blades may be shifted longitudinally of the machine by means of the adjusting-wheel 360 provided at the end of the adjusting spindle 361 rotatably mounted in the standards 334 and 332. Upon this spindle are keyed the bevel gears 363 meshing with similar gears 364 keyed on the threaded spindles 335. The threads on both portions of the latter being identical, will cause the stop-blades to maintain their correct distance while traveling either way.

As soon as the tag-blanks are stopped by the stop-blades 339, they are pushed transversely of the machine toward the patching and eyeleting devices by means of two joggers 365 mounted for longitudinal and angular adjustment, by means of set screws 366 placed on the collars 367, on the longitudinally disposed jogger-shaft 368 rotatably mounted in a bearing block 369, Figs. 29 to 35. This bearing block has a grooved base 370 which is mounted for sliding movement on a transverse rail 371 supported at the inner end by the bar 291 and at the outer end by the support 372 fastened on top of the main housing. The bearing block is held on this rail by a plate 373 screwed thereon and is locked in the selected position by means of a pressure screw 374. At their free ends the joggers have curved tail-pieces 375 the purpose of which is to prevent the joggers catching into the conveyor belts, by pushing the latter gradually aside when interfering with the rotation of the joggers.

Fastened on the jogger-shaft 368, close to the bearing block, is a rack-pinion 376 which is adapted to engage the teeth of the rack-bar 377 passing through the slotted guide-plate 378 removably secured on the bearing-block by a clamping screw 379. The inner end of the rack-bar has no teeth and slides in a groove provided in a substantially horizontal base 380 carried by a post 381 bolted on top of the housing 30. Cross-strips 382 secured to this base hold the rack in place.

Upon the rack is fastened by screws 383 a plate 384 at one side of which is an extension 385 carrying at the end an anti-friction roller 386.

386. This plate is slidably secured to the base by screws 387 engaging slots 388 cut in the former.

5 The joggers are normally held in the substantially horizontal, inoperative, position shown in Figs. 29 to 32 by means of a tension spring 389, the inner end of which is attached to a post 390 secured on the plate 384 while the other end is fastened to an adjusting 10 screw 391 carried by a stationary post 392 supported by the base 380.

At one side of the stand 95 of the punch-press is rockably mounted on a bolt 393 a lever 394 having at its lower end an elongated 15 slot 395 in which operates the roller 386, and on the rear of this lever is provided a lug 396 which is adapted to be engaged by the strike-head 397 fastened to the lower end of a vertical plunger-rod 398 which is adjustably set 20 cured by a set-screw 399 to a horizontal bracket 400, Fig. 29, bolted on top of the upper traveling head 97 of the punch-press.

The strike-head 397 engages the lug 396 on the downward stroke of the upper traveling-head 97 slightly before the patch-punches 25 101 and 112 cut the patches in the patch-strips 165. This engagement causes the lever 394 to rock counterclockwise, thereby pushing the rack 377 to the right (Fig. 29) and im- 30 parting to the joggers a clockwise rotation which pushes the tag-blanks toward the patching and eyeleting devices.

When the joggers are to be adjusted transversely on the rail 371, it is preferable to 35 loosen the top guide-plate 378 to permit of disengaging the rack 377 from its pinion 376, and upon loosening the pressure screw 374, the bearing block may be slid along the rail without causing the joggers to rotate and 40 interfere with the conveyor belts. The jogger-shaft 368 is held in the bearing-block, against longitudinal displacement, by the pinion 376 and a collar 401.

Operation

Having described the principal parts of my tag making machine and the operation of the individual cooperating devices, the successive steps performed in making a finished tag may be briefly recapitulated:

Assuming that a stack of tag-blanks of the required size has been piled up on the feed carriage 36 and properly guided thereon, the stop blades 339 and the joggers 365 are first 55 adjusted to suit the size of the tag, and the electric motor 14 is started to operate the machine.

On the first forward movement of the feed carriage 36 the first tag is fed to the continuously moving feed-conveyors 64, 65 by the push-fingers 39. This tag passes over the latch-finger 196 whereby the patch-strip 165 is fed into the patch-press, while the first tag keeps moving forward. This tag then 65 engages the control-trigger 289 whose pull-wire

288 acts on the lever 286, thereby connecting the latch 281 to the slide-bar 276 (Figs. 46, 47), and the eyelet feeding device is operated, even though there be no tag-blank in eyeletting position.

70 Before the first tag has reached the proper operative position before the patch-press, the feed-carriage has moved backward and the cam-rail 357, by engaging the roller 356 on the lever 352 which actuates the square shaft 341, causes the stop-blades 339 to operate idly. (See Figs. 17 to 20 and 24 in particular.)

The feed-carriage now moves forward for the second time, thus feeding a second tag-blank into the conveyor system. As this second tag engages the latch-finger 196 the patch-strip is fed forward into the patch-press for the second time.

80 The connecting rods 128, 129 (Figs. 8, 9) of the patch-press now move the patch-punches 101 and 112 toward each other into punching position. In the meanwhile the feed-carriage has moved backward for the second time and caused the stop-blades to arrest the forward movement of the first tag, 85 when the latter is in correct longitudinal punching position.

85 However, before the patch-punches attack the patch-strips 165 and the first tag, the strike-head 397 (Figs. 29 to 31) actuates the rack 377 whereby said tag is pushed transversely of the machine into final punching position by the first jogger 365. The first tag is now punched and patched.

90 The feed-carriage now moves forward for the third time whereby the stop-blades 339 are lowered to enable the first tag to move toward the eyeleting machine and the second tag toward the patch-press, also, a third tag is fed into the conveyor system. This third tag, when passing over the latch-finger 196 causes the patch-strip to be fed forward for the third time to supply patches for the second tag. Also, when passing past the trigger 289, this tag causes the pull-wire 288 to 100 actuate the lever 286, whereby the eyelet feeding raceway is brought into operative position with the eyelet pilot 222 and eyelet-setter 241, for the purpose of applying the metal eyelet to the first tag, and also cutting 105 the corners thereof.

110 When the first tag reaches a position in front of the eyelet-setter, its forward travel is arrested by the second stop-blade 339, on the third backward movement of the feed-carriage, the first stop-blade 339 also stopping at the same time the second tag directly in line with the patch-press. The downward movement of the upper punch 101 of the latter will, of course, operate the joggers 365 115 which will push the first and second tags transversely of the machine toward the eyeletting device and the patch-press, respectively.

120 When the now finished first tag leaves the 125

eyeleting device it is discharged on the table 330, the second tag now comes into operative position for the eyeleting device, the third tag is positioned to be acted upon by the 5 patch-press, and a fourth tag has been fed into the conveyor system on the fourth forward movement of the carriage, and so forth.

It will be noted that when the machine operates normally, there is a tag-blank simultaneously under the patch-press and the eyeleting device, so that the patch stop-blades and the joggers will operate on two tag-blanks at the same time. The functions performed by each device are also substantially 15 simultaneous. It is evident that in order to obtain the proper sequence in the operations required, the cams and other actuating means must be properly adjusted.

As stated heretofore, tags without eyelets 20 may be produced by simply removing the wire 288 of the control-trigger 289. Also, tags with eyelets, but without patches, or with a patch on one side only, may be produced by not feeding the patch-strips through the 25 patch-press, or feeding but one strip, as the case may be.

A machine of my invention, on account of its relative cheapness and reduced size, is of great value to printers, as it enables them to 30 individually produce tags independently of a relatively few firms which have specialized in this industry, which firms are often very far away from the printers and, therefore, rarely able to assure prompt deliveries, either 35 on account of the distance or because of business congestion. A printer provided with such a machine, may easily and quickly supply himself with the required amount of flat stock of the desired quality to fill an order, 40 from his regular local source of supply, thus eliminating the expensive necessity of carrying large quantities of raw tag material, as is the general practice of specialty tag makers. Furthermore, this machine opens a new 45 field of activity for the individual printers in that it enables them, with a relatively small capital-investment, to engage into a specialty which was formerly closed to most of them, and to print tags of different sizes and quality 50 for the local trade either in multiple or singly, on their own, ordinary, printing presses.

As will be understood, there may be slight changes made in the construction and arrangement of the details of my invention without departing from the field and scope of the same, and I intend to include all such variations, as fall within the scope of the appended claims, in this application in which 60 one form only of my invention has been disclosed.

I claim:

1. In a tag making machine, a patch punching and pressing device; an eyeleting device; 65 a system of conveyor belts adapted to convey

tag-blanks to said devices, and means for operating said devices and conveyor-belts in proper speed relation.

2. In a tag making machine, a patch punching and pressing device; an eyeleting device; 70 a system of conveyor belts adapted to convey tag-blanks to said devices, and unitary means for operating said devices and conveyor belts in proper speed relation.

3. In a tag making machine adapted to 75 make tags of the character described from pre-cut tag-blanks, a support for a stack of tag-blanks; a patch punching and pressing device; an eyeleting device; a system of conveyors adapted to convey the tag-blanks to said devices; feeding means to feed one tag at a time to the conveyors and unitary means for actuating said devices, conveyors and feeding means in proper speed relation.

4. In a tag making machine adapted to 80 make tags of the character described from pre-cut tag-blanks, a support for a stack of tag-blanks; a patch punching and pressing device; an eyeleting device; a system of conveyors adapted to convey the tag-blanks to 85 said devices; feeding means to feed one tag at a time to the conveyors; stopping means for stopping the tag-blanks in operative position relative to said patch punching device and eyeleting device, and unitary means for 90 actuating said devices, conveyors, feeding and stopping means in proper speed relation.

5. In a tag-making machine adapted to 95 make tags of the character described from pre-cut tag-blanks, a support for a stack of tag-blanks; a patch punching and pressing device; an eyeleting device; a system of conveyors adapted to convey the tag-blanks to said devices; feeding means to feed one tag-blank at a time to the conveyors; unitary adjustable 100 stopping means for stopping the tag-blanks in operative position relative to said patch punching device and eyeleting device, and unitary means for actuating said devices, conveyors, feeding and stopping means in proper speed relation.

6. In a tag making machine adapted to 105 make tags of the character described from pre-cut tag-blanks, a patch punching and pressing device adapted to punch the patches from a continuous patch-strip; an eyeleting device; a patch-strip feeding device; a system of conveyors adapted to convey tag-blanks to said devices; means for operating 110 said devices and conveyors in proper speed relation, and means actuated by moving tag-blanks for controlling the operation of said patch-strip feeding device.

7. In a tag making machine adapted to 115 make tags of the character described from pre-cut tag-blanks, a patch punching and pressing device adapted to punch the patches from a continuous patch-strip; an eyeleting device; a patch-strip feeding device; a system of conveyors adapted to convey the tag-blanks to 120

said devices; means for operating said devices and conveyors in proper speed relation, and means actuated by the moving tag-blanks for controlling the operation of said eyeleting device.

5 8. In a tag making machine adapted to make tags of the character described from pre-cut tag-blanks, a support for a stack of tag-blanks; a patch punching and pressing device; an eyeleting device; a system of conveyors adapted to convey the tag-blanks to said devices; feeding means to feed one tag-blank at a time to the conveyors, and means for pushing the tag-blanks at right angles to their direction of travel to place same in operative position relative to said patch-punching device and eyeleting device.

10 9. In a tag making machine adapted to make tags of the character described from pre-cut tag-blanks, a support for a stack of tag-blanks; a patch punching and pressing device; an eyeleting device; a system of conveyors adapted to convey the tag-blanks to said devices; feeding means to feed one tag 15 at a time to the conveyors, and unitary longitudinally and transversely adjustable means for pushing the tag-blanks at right angles to their direction of travel to place same in operative position relative to said patch-punching device and eyeleting device.

20 10. In a tag making machine adapted to make tags of the character described from pre-cut tag-blanks, a patch-punching and pressing device and a corner punching shear actuated thereby; a patch-strip feeding device; a system of conveyors adapted to convey tag-blanks to said devices; feeding means to feed one tag-blank at a time to the conveyor, and unitary means for actuating said devices, 25 conveyors and patch-strip feeding means in proper speed relation.

In testimony whereof I affix my signature.
SAMUEL E. ALLEN.
